(57) **CLAIM**

The ornamental design for a plush toy, as shown and described.

DESCRIPTION

FIG. 1 is a front view of the new design for a plush toy holding a daisy;

FIG. 2 is a right side view thereof;

FIG. 3 is a left side view thereof;

FIG. 4 is a top view thereof; and,

FIG. 5 is a bottom view thereof.

The rear side is plain and unornamented.

The subject matter shown in broken lines forms no part of the claimed design.
